BOTTLE

John H. Currie, Jr., Huntington, N. Y., assignor to Nehi Corporation, Columbus, Ga., a corporation of Delaware

Application April 9, 1956, Serial No. 40,974

Term of patent 14 years

(Cl. D58—8)

I claim:

The ornamental design for bottle, substantially as shown.
